KNITTING MACHINE

Ralph Norman Toone, Wollaton Park, England,
assignor to B. Toone (Nottingham) Limited,
Nottingham, England

Application October 16, 1943, Serial No. 506,569
In Great Britain August 25, 1942

4 Claims. (Cl. 66—134)

This invention is for improvements in or relating to knitting machines, and is particularly, but not exclusively, concerned with splicing mechanism in seamless hose and half hose machines. In producing splicing on a circular knitting machine it is usual to introduce the splicing thread into knitting activity for a predetermined portion of each course, the splicing thread floating chord-like in the interior of the needle circle for that portion of each course during which it is not knitted. These floats are in the majority of instances subsequently cut out by hand, although prior U. S. Patent No. 2,295,450, granted September 8, 1942, to Bernard T. Cole, describes mechanism wherein the thread or yarn is severed at each withdrawal so that the formation of floats is obviated. It is desirable that at each re-introduction of the yarn or thread to the needles said threads shall be fed with accuracy to a predetermined needle, and the present invention has for its object to provide means whereby the withdrawn thread is so positioned that this accurate re-introduction results. It will be appreciated, however, that the present invention is not restricted in its application to splicing mechanism, but may be applied to other mechanisms wherein a thread or yarn is introduced into the fabric at intervals. Specific examples are mechanisms for the production of split work, or plating.

As viewed from one aspect, the invention provides in or for a knitting machine having a yarn feeder displaceable between feeding and non-feeding positions, a yarn-control device located or adapted to be located at the plain side of the needles, remote from the feeder, in a stationary attitude to receive a withdrawn yarn upon movement of the feeder to non-feeding position and to position said yarn for re-introduction to the needles upon movement of the feeder to feeding position, comprising a catch for receiving the yarn but permitting it to draw out endwise therefrom. Preferably the device incorporates a narrow gap into which the thread is carried by movement of the feeder to non-feeding position, and a hook that engages the thread upon movement of the feeder towards feeding position and diverts said thread into the hook interior constituting the catch.

These and other features of the invention set out in the appended claims are incorporated in the construction that will now be described with reference to the accompanying drawings, which illustrate an improvement in the apparatus dis-

closed in my prior U. S. Patent No. 2,357,708, granted September 5, 1944, and in which

Figure 1 is a front elevation (looking from the interior of the needle circle) and Figure 2 is a side elevation showing the device incorporated in mechanism according to the aforesaid patent;

Figures 3-7 are views showing the said device in front elevation and illustrating its action;

Figure 8 is a sectional plan of the device;

Figure 9 is a plan of a detail.

At the interior of the needle circle there is mounted a device 170 according to this invention which functions to receive the splicing or other thread S when the feeder 10 is raised to the inoperative position and to position the said thread accurately for its re-introduction to the needles N upon descent of the feeder. This device 170 is normally stationary. Viewing the said device 170 from the interior of the needle circle and

considering the needle cylinder to rotate anti-clockwise so that the needles pass at the rear of the device from right to left between said device and the feeder, the said device consists of two plate members 171, 172, the main one (171) of which is cut in its front face with a vertical groove which is adjacent to its right-hand edge. In this groove the second plate member 172 is secured by a screw or other means 173 in such manner that the left-hand edge of the second member is spaced (at least for the lower part of

its height) from the left-hand edge of the groove and the rear face of the second member is spaced from the face of the rebate or groove. Thus there is provided between the two members an open-ended gap 174 which is substantially L-shaped in horizontal cross section (Fig. 8). The second member 172 is provided with an upwardly-directed hook portion 172a at its right-hand edge, the tip of the hook being curved

40 backwards toward the face of the groove (so as to encroach into the gap 174) and being located slightly to the left of the projecting lip or wall 171a formed on the first member 171 at the right-hand edge of the groove. The interior of the hook (the catch aforesaid) is in the form of a vertical slit 175. The arrangement of this device 170 is therefore such that as the feeder 10 rises to the non-feeding position the withdrawn yarn S passes between the two plate

45 members into the L-shaped gap 174 and is therefore diverted from its straight run (Fig. 3). At the extremity of the upward movement of the feeder 10 the said diverted thread lies above the tip of the hook and is further diverted from 50 its approximate L-shape by the aforesaid wall or

55

lip 171a around which it extends back to the feeder (Fig. 4). When the feeder 10 commences (Fig. 5) to descend to the feeding position the thread is carried down over the rearwardly-directed tip of the hook 172a so that it passes into the slit or hook interior 175. At this stage (Fig. 6) the thread S runs from the feeder eye 10' across the needle circle to the right-hand edge of the hook 172a, across the front face of the latter into the slit or interior 175 of the hook, thence behind the second plate member 172 and between the latter and the front face of the groove, and then outwards through the gap 174a between the left-hand margin of the groove and the left-hand margin of the second plate member 171 which its protruding free end is presented. The device 170 is so positioned that the portion of the thread that extends from the feeder 10 to it extends radially across the needles N. As the feeder further descends (Figs. 7 and 8) this portion of the thread is lowered between the needles N and is therefore taken with accuracy by a predetermined needle. This accurate reception is further enhanced by the fact that the right-hand edge of the hook 172a protrudes beyond the corresponding edge of the first member 171 and is curved outwards somewhat towards the right so that as the thread descends it is moved slightly towards the right. Finally, as soon as the thread is taken by the needles the rotation of the latter causes it to draw out endwise from the device 170.

The reception of the thread S in the device 170 is facilitated by providing a throat 177 which leads to the aforesaid L-shaped gap 174. For this purpose the lower edge of the first plate member is curved downwards to the left, while the left-hand edge of the second plate member extends straight downwards beyond said curving edge.

The application of the device 170 to a known form of knitting machine mechanism will now be described. The feeder 10 (e.g., a splicing feeder) is operated by push rod 11 in known manner; it carries a pin 18 which as the feeder is raised to the non-feeding position eventually engages a screw 17 projecting from an arm 16 pivoted at the feeder axis 14. The rest position of this arm 16 is determined by an adjustable tappet screw 20 normally bearing on a part of the feeder bracket, and the arm carries a yarn eye 22 and a yarn-retarding device 19 (conveniently in the form of a pair of spring-pressed cymbals), the yarn S running from said eye 22, through the cymbals 19, to the eye 10' of the feeder 10. A cutter block 27 carrying knives 29, 30 is supported inside the needle circle by a knife arm 26 pivoted at 25. This cutter is capable of being raised to inoperative position (e.g., at the termination of splicing) by thrust rod 49. The movable blade 30 is operated to cut, by a lever 61 pivoted on the knife arm 26 at 62; the inner end of this lever 61 overlies an adjustment screw 28 on arm 16. As the feeder 10 is raised to withdraw the yarn S from the needles the withdrawn yarn is carried round into the cutter 29, 30: the feeder raises arm 16 through the medium of pin 18 and screw 17 and the arm rocks the cutter lever 61 (through the medium of screw 28) to operate the cutter. Obviously, the timing of the cutter in relation to the withdrawal of the yarn can be adjusted by screws 17, 20 and 28. When the feeder 10 is lowered to re-introduce the free end of yarn to the needles the arm 16 descends with it until brought to rest by screw 20. Thereafter the

feeder descends alone and the grip of the cymbals 19 on the yarn causes the free yarn end to be drawn back through the feeder eye 10'. The extent of this draw-back, and the length of yarn end, can be predetermined by adjustment of screw 20.

The improved device 170 according to the present invention is suspended from the platform 80 which projects across the needle circle from the top of the feeder bracket 81 and is moved into and out of operative position as the cutter arm 26 is so moved. That is to say at the commencement of the spliced or like area the device 170 is lowered to the operative position by the cutter arm 26 and at the termination of said area it is raised to the inoperative position with the cutter arm 26 and during the production of the said area said device remains stationary in the operative position. To this end the said device 170 is provided with a spindle 82 which extends upwards through a sleeve 83 fixed on the said platform and is biased in the upwards direction by a compression spring 84 encircling the spindle. Conveniently a pin 85 projects from the spindle 82 through a vertical slot 86 in the sleeve 83, into a housing sleeve or thimble 87, the spring 84 being interposed between the closed upper end of thimble 87 and the top of fixed sleeve 83. The device may therefore be raised by hand if required. Projecting from the cutter block 27 or from another suitable part moving with the cutter arm 26 there is a small arm or other projection 88 which is adapted to overlie a pin or other shoulder 89 on the said device 170 so that when the cutter arm 26 descends the device 170 is lowered and when the cutter arm rises the device is raised by the aforesaid compression spring 84.

According to a further subsidiary feature of this invention the aforesaid platform 80 is employed as a guide plate to guide the various threads to the battery of interchangeable yarn feeders, and means are provided for mounting said platform on the existing feeder bracket 81. As is well known and as is shown in the aforesaid Letters Patent No. 2,295,450 the feeder bracket is of inverted U-shaped construction. The upper surface of the cross bar 81a thereof is curved and difficulty is experienced in mounting any attachment thereon. According to the present invention there is employed a mounting block 90 having in its undersurface a recess or groove which is V-shaped in cross section (or otherwise has divergent flanks) so as to seat on the curved upper surface aforesaid. This mounting block 90 is secured by a screw 91 which passes down through it into a tapped hole in the cross bar 81a. The platform 80 has two side walls or lips 80a at its underside (which may also be provided with porcelain eyes) and these side walls are carried back as lugs 80b to receive the mounting block 90 closely between them. The said lugs 80b are provided with horizontal slots 92 and through each slot a screw 93 extends horizontally into the adjacent end of the mounting block 90. The said slots 92 therefore afford an adjustment of the platform 80 towards and away from the centre of the needle circle. It will be understood, of course, that the device 170 may be mounted on any other fixed part of the apparatus.

I claim:

1. In a knitting machine of the kind having needles and a yarn feeder displaceable between feeding and non-feeding positions; a yarn-control device located at the plain side of the needles

in a stationary attitude for receiving a withdrawn yarn upon movement of the feeder to non-feeding position and for positioning said yarn for re-introduction to the needles upon movement of the feeder to the feeding position, which device is stationary during displacement of the feeder between feeding and non-feeding positions and comprises a narrow gap, extending transversely of the run of the yarn and in the general direction in which the yarn is moved upon movement of the feeder to non-feeding position, for reception of the yarn upon said movement to non-feeding position; a hook for receiving the yarn upon movement of the feeder to feeding position; and a tip to said hook, encroaching into the gap, for engaging the yarn upon the last-said movement and for diverting it into the hook.

2. A machine according to claim 1, having the gap formed between two adjacent members one of which is formed with the hook, and having the tip of the hook deflected towards the other member into the gap.

3. In a knitting machine of the kind having needles, a yarn-feeder displaceable repeatedly between feeding and non-feeding positions to incorporate its yarn intermittently in the fabric, and a severing device located at the plain side of the needles to sever the yarn at each with-

drawal; a yarn-control device located at the plain side of the needles for receiving the withdrawn yarn upon movement of the feeder to non-feeding position and for positioning the yarn for reintroduction, and means supporting said control device between the severing means and the needles in a stationary attitude during the aforesaid movement of the feeder, which control device is formed with a gap for the entry of the yarn upon movement of the feeder to non-feeding position, and a hook for receiving and supporting the yarn extending through the gap but permitting it to draw out endwise therefrom upon movement of the feeder to feeding position, which hook has a tip protruding into the gap to engage the yarn and to divert it into the hook.

4. For a combination according to claim 1, a device comprising two members whereof one has a rebate near one margin and the other is disposed in said rebate with its face spaced from the face of the rebate and an edge spaced from the edge of the rebate whereby there is formed between said members a narrow gap of bent section extending from the said margin to the edge of the rebate; and a hook, formed in the other said member, having its tip adjacent to the said margin and encroaching into the gap.

RALPH NORMAN TOONE.
